UNITED STATES PATENT OFFICE.

HENRY SIMON, OF LAGUNA BEACH, CALIFORNIA.

MITER-BOX.

1,259,920.

Specification of Letters Patent. Patented Mar. 19, 1918.

Application filed October 12, 1916. Serial No. 125,272.

To all whom it may concern:

Be it known that I, HENRY SIMON, a citizen of the United States, residing at Laguna Beach, in the county of Orange and State 5 of California, have invented a new and useful Miter-Box, of which the following is a specification.

This invention has reference to miter boxes, and its object is to provide a miter box construction having the advantages of both a wooden and a metal miter box, but avoiding certain disadvantages of each 10 while at the same time providing further advantages not found in either of the ordinary types of miter boxes.

In accordance with the present invention the miter box comprises a body or base member which may be made of metal for compactness and strength, and on opposite 20 sides the body member is provided with rows of posts and wooden pins constituting guides for the saw and permitting the use of either an ordinary hand saw or a back saw. The pins and posts have co-acting 25 parts permitting the firm lodging of the pins in the posts in different adjusted positions or the ready loosening of the pins from the posts for readjustment or removal.

The invention provides for certain fixed 30 angles of cut comprising the more generally used angles and their opposites, except that the 90° cut has no opposite, and provides adjustable means whereby other angles of cut than the fixed ones may be made, the 35 opposite cuts to the adjustable angles being automatically provided for.

The invention has all the advantages of an all metal miter box with all the adjustments there provided, with the further advantage that with any angle of cut provided, except 90°, the opposite angle is present as in the ordinary wooden miter box, but with a far greater range of angles than is provided in the ordinary wooden 45 miter box.

The invention will be best understood from a consideration of the following detailed description, taken in connection with the accompanying drawings forming part 50 of this specification, with the further understanding that while the drawings show a practical form of the invention, the latter is not confined to any strict conformity with

the showing of the drawings, but may be changed and modified so long as such 55 changes and modifications come within the scope of the appended claims.

In the drawings:—

Figure 1 is a plan view of a miter box constructed in accordance with the invention and representing a form in which the basic portion may be made of sheet or stamped metal, and in this figure some parts have been broken away and some parts have 60 been omitted.

Fig. 2 is a side elevation of the structure shown in Fig. 1 with some parts broken away and some parts shown in section.

Fig. 3 is an end elevation of the structure of Fig. 1 as seen from the right hand 70 end thereof, some parts being broken away and in section to reveal more distant parts.

Fig. 4 is a detail sectional view on the line 4—4 of Fig. 1, but drawn on a larger scale.

Fig. 5 is a section on the line 5—5 of Fig. 4.

Fig. 6 is a section on the line 6—6 of Fig. 5.

Fig. 7 is a section similar to Fig. 5 but 80 taken through one of the adjustable pins and tubular post therefor.

Fig. 8 is a section on the line 8—8 of Fig. 7.

Fig. 9 is a perspective view of the base 85 block or carrier shown in Figs. 7 and 8.

Fig. 10 is a plan view of a cast metal structure embodying the invention, certain parts being broken away to reveal some 90 distant parts and the pins being omitted.

Fig. 11 is a side elevation of the structure of Fig. 10 with the pins in place.

Fig. 12 is an end elevation of the structure shown in Fig. 11, the view being taken from the right hand end of the showing of 95 Fig. 11.

Referring first to Fig. 1 and associated figures there is shown a base member 1 provided with longitudinal side channel portions 2, 3, respectively, extending the length 100 of the base member, which latter is usually longer than wide. This form of the invention permits the production of the base member of sheet metal, thus providing a light, and at the same time a strong member 105 particularly resistant to breakage. The top

of the base member may be in the form of a plate 4 designed to support a wooden strip or floor piece 5 upon which the work to be sawed is placed, and which also provides a means into which the saw teeth may enter slightly without harm, so as to completely traverse the work.

In order to brace the channel members they are connected at each end at the bottom by strips 6.

At various points along both channel portions the latter are pierced by alined passages 6, 7, respectively, each pair of passages constituting in effect a socket. Engaged in each socket is one end of a tubular post 8 slit or slotted longitudinally on diametrically opposite sides, the slots being shown at 9. The tubular posts stand upright in the working position of the miter box, and the slots 9 enter the top of each tubular post and extend to a point below the top surface of the board 5 and may extend to or nearly to the top member 4 of the basic member 1. The posts 8 are secured in any suitable manner in the sockets receiving them, so that when once set the posts 8 are fixed in position with respect to the base 1. Each post 8 on one side of the miter box has its slots 9 alined with similar slots in another post on the other side of the miter box, wherefore the posts are in effect arranged in pairs on the opposite sides of the miter box. For instance, in the structure of Fig. 1 there are five posts 8 on each side of one end portion 35 of the miter box, these posts occupying about half the length of the miter box as illustrated in Fig. 1. The end posts 8 on one side of the miter box match the end posts 8 on the other side of the miter box, except that each end post on one side has its matching end post at the opposite end of the series of posts on the opposite side and the parts are so arranged and disposed that with the slots 9 in alinement the plane 45 of such alinement is arranged at forty-five degrees to the longitudinal center line of the miter box. The middle posts of the series of five on each side of the miter box have their slots 9 in alinement in a plane 50 perpendicular to the longitudinal center line of the miter box, and, therefore, such plane is at right angles to the longitudinal center line of the miter box. The alined slots of the remaining posts on opposite sides of the 55 center post and between the center post and the end posts have their matching slots in planes at sixty-seven and one-half degrees to the longitudinal center line of the miter box.

60 Adapted to each post is a pin 10, such pin being conveniently made of hard wood. The pin is of such diameter as to fit snugly in a respective post 8 and may enter the top of the post and extend close to the bottom 65 thereof. Each pin 10 is provided at what

constitutes its upper end in the working position of the parts with a head 11 of greater diameter than the diameter of the body of the pin, and where the head and pin join there is formed a substantially annular 70 groove 12 suitably tapered to have the upper end 13 of the post firmly engaged therein, such upper end being correspondingly tapered. Extending longitudinally and diametrically of the pin 10 is a slot 14 traversing the head 11 and entering the pin 10 to a depth sufficient to bring it at or slightly below the top face of the board 5 when the pin is properly seated in the corresponding post.

When the pins 10 are placed in the posts 8 the slots 14 are brought into substantial alinement with the slots 9 and the slot 14 of any particular pin 10 is made to aline with the slot 14 in the companion pin on 85 the other side of the miter box. When this is accomplished a blow delivered upon the head 11 of the pin serves to wedge it tightly on the beveled or wedge-shaped upper end 13 of the post containing the pin, so that the 90 pin becomes effectively immovable, so far as its relation to the post is concerned. If it be desired at any time to remove a pin, a blow on the under side of the head 11 is sufficient to loosen the pin and permit its 95 withdrawal, for while the pin fits snugly in a respective post, such fit is not so close as to prevent the ready removal of the pin when it is needful to substitute another pin therefor.

When the pins have been properly set in the posts 8 the miter box is provided with saw guides formed by the pins for the production of certain cuts, usually those customarily provided for in wooden miter boxes. 105 The saw guides so far as the parts engaging the saw are concerned are wood and, therefore, an ordinary hand saw may be used in the miter box although of course a back saw of proper size may be employed. In 110 this respect the miter box is similar to the ordinary wooden miter box and has the advantage possessed by the wooden miter box, in that for each angular cut, other than ninety degrees, the opposite cut may be made 115 without any adjustment of parts such as are required by the iron miter box. With the ordinary wooden miter box the repeated use of the saw, its insertion and removal, results in widening the slots, so that after a while 120 the miter box has lost its reliability and a new miter box must be obtained. In the miter box of this invention when the wooden pegs become worn they are readily replaced by new pegs and may be readily adjusted 125 into proper relation by any one without the exercise of any special care. By inserting the pegs loosely in the columns in which they fit snugly enough for adjusting purposes, the pegs may be properly alined by inserting 130

a saw, whereupon on the removal of the saw the pegs may be driven tightly into place by blows delivered on the heads 11. The tubular posts 8 provide means for insuring the proper positioning of the pegs or pins 10 when alined by an inserted saw.

In order to provide a backing for the work, a strip 15 is applied to the top of the channel 2, being held thereto by bolts 16, or in any other appropriate manner, and this strip has a rising flange along one edge, which flange may reach close to the under surface of the heads 11 on the particular side of the miter box. The flange is in fact a multiple flange represented by numerous sections 17 spaced apart to permit the passage of the saw to and through the slots in the respective posts 8 and pins 10.

Erected on the channel 2 are other posts 8^a which may be in all respects similar to the posts 8 as to their spacing and being provided with slots 9^a considerably wider than the slot 9 of the posts 8, this permitting a turning of the pins 10 therein to adjust them for different angles than can be made with the pins 10 in the posts 8.

The channel 3 at that end opposite the posts 8^a is provided with a longitudinal slot 18, and this portion of the channel supports blocks or carriers 19 each having a central elongated rib or spline 20 on what constitutes its under face to engage in the slot 18 and guide the block along the upper face of the channel 3. To hold the blocks from lifting from the channel each block has a threaded pin 21 extending into the channel 3 and there receiving a nut 22 confining a link 23 against a washer 24 surrounding the pin 21 and spacing the link 23 from the rib 20 and the under face of the top member of the channel 3. The parts are so adjusted that the blocks 19 may be moved toward or from each other along the top of the channel 3 to equal extents. To accomplish this the links 23 are brought together at the ends remote from the blocks 19 and are there joined by a bolt 25 extending through a slot 26 in a bar 27 arranged transversely of the miter box from the channel 2 to the channel 3. A nut 28 on the bolt 25 serves to confine the connected ends of the links 23 to the bar or guide strip 27. To lock the parts in adjusted positions one of the pins 21 instead of being provided with a nut 22 carries a tail nut 29 provided with a manipulating handle or tail 30 projecting through a slot 31 in one upright wall of the channel 3, so that the parts may be conveniently clamped in adjusted positions by a manipulation of the tail nut.

Rising from each block 19 is a tubular post 8^b having a circumferentially extended upright slot 9^b. The posts 8^b carry pins 10 like the other posts.

By the use of the posts 8^a, which are equi-

distantly disposed along the channel 2 and on the opposite side of the miter box from the adjustable posts 8^b, the posts 8^a with their pins 10 and the posts 8^b with their pins 10 permit the setting of the saw-guiding pins to all the angles usually provided with an iron miter box and angles which are not provided for in the other end of the miter box. With the four equi-distantly disposed posts 8^a and the two adjustable posts 8^b with the rotatably adjustable slotted pins 10 any angles from forty-five to ninety degrees are obtainable, and when any angle is set the opposite angle is also set automatically, whereby the opposite angles may be cut to fit without any adjustment whatever of the miter box to obtain the opposite angle. With the customary iron miter box, if a cut is made at one angle the miter box must be reset to obtain the opposite cut. This avoids any liability of a faulty resetting of the miter box to obtain the opposite cut after the first cut is obtained.

The board 5 may be secured in place by screws 32, or in any other suitable manner.

In the structure of Fig. 10 and associated figures there is a base member 33 formed by casting, and tubular posts 34 and 34^a corresponding to the posts 8 and 8^a of the structure of Fig. 1 may be cast separately from the base 33 and secured thereto by screws 33^a. Furthermore, the posts 34 and 34^a are joined together by webs 35 which may be cast in one piece with the posts and with the base 33. A backing plate 36 corresponding to the backing plate 17 of Fig. 1 is also cast with the base 33 and may where adjacent to corresponding posts 34 and 34^a be integral therewith. Of course, the backing plate 36 is made in a suitable number of sections for the same reason that the web 17 is made multi-sectional.

The base 33 where covered by the board 5 is formed with numerous openings 37 to reduce the weight of the structure. A web 38 between certain of the openings replaces the bar 27 of Fig. 1, and in this web 38 is a slot 39 for receiving a bolt 40 joining links 23 connecting the blocks 19 as before, the base 33 being provided with a longitudinal slot 18^a corresponding to the slot 18 of Fig. 1. The other parts being of like construction need no particular description. The operation of the structure of Fig. 10 and associated figures is like that of Fig. 1 and associated figures and requires no special description.

What is claimed is:—

1. A miter box comprising a basic portion having upstanding holders on opposite sides of the work-holding space, and pins mounted and rotatable in the holders and provided with saw-receiving slots, the entering ends of the holders and corresponding portions of the pins having coacting parts in wedge 125

relation to bind the pins and hold them in adjusted position, said pins projecting beyond the holders and there enlarged to provide heads whereby the pins may be loosened 5 from wedging in the holders by forces directed against the heads on the holder sides thereof.

2. A miter box provided with upstanding holders, and wooden pins for entering the 10 holders, the pins when in the holders projecting above the latter and there having expanded heads with grooves to receive the upper ends of the holders, and said upper ends of the holders entering the grooves and 15 wedging therein to hold the pins in adjusted positions.

3. A miter box, comprising a basic portion with upstanding tubular holders on opposite sides, each holder having diametrically 20 opposite slots through its walls and extended in the direction of the length of the pin to receive a saw, and wooden pins adapted to the tubular holders, each pin having a head at one end to override the corresponding end 25 of a holder and provided with a diametric slot extending through the head and longitudinally of the body of the pin, each pin having in the face of the head toward the stem of the pin an annular groove and each 30 holder being beveled on the end toward the head of the pin, whereby the pin may be wedged on the tube to hold it in adjusted positions.

4. A miter box provided on one side with 35 a plurality of upstanding fixedly spaced saw guides and on the opposite side with upstanding saw guides and supports therefor, said supports being movable simultaneously in opposite directions lengthwise of the box 40 to adjust them alike with relation to the saw guides on the opposite side of the box, whereby the guides may be adjusted for various angles of cut and also provide for the opposite angles of cut without further adjustment.

5. A miter box having a pair of simultaneously and oppositely movable saw guides on one side of the box and a plurality of equi and permanently spaced saw guides on 50 the other side of the box to provide various angles of cut and at the same time the opposite angles of cut by the simultaneous opposite movement of the individual guides of the pair of saw guides.

5. A miter box having a set of matching saw guides disposed on opposite sides of the box and all in fixed relation to provide certain permanently set angles of cut and the corresponding opposite angles of cut, and 60 another set of guides disposed on opposite sides of the box, those guides of the second set on one side of the box being in fixed relation to the box, and those guides of the second set on the opposite side of the box 65 having means for causing their simultaneous

movement in opposite directions lengthwise of the box to provide for various angles of cut and the opposite angles of cut.

7. In a miter box, upstanding holding means, and a cylindrical wooden saw-guiding device provided at one end with a laterally extending head, and having a longitudinally extended diametric slot entering the device through the head, the saw guiding device and the holding means therefor having coacting parts for wedging the device and the holding means together when in operative position.

8. A metal miter box provided on opposite sides with upstanding tubular metal posts 80 having diametrically opposite longitudinal slots, and wooden pins each having a laterally expanded head at one end with a shank to fit a tubular post for rotation therein and having a longitudinal slot extending through 85 the head and part of the length of the stem to correspond to the slots in the posts, the ends of the posts where receiving the pins entering the heads of the pins and wedging therein, whereby the pins may be initially 90 adjusted and when worn may be loosened in the posts by blows delivered to the under side of the heads.

9. A miter box having saw guides on opposite sides of the work receiving space, 95 with those guides on one side of the box held thereto against movement lengthwise of the box and greater in number than the guides on the opposite side of the box, the second-named guides being adjustable to co-operate interchangeably with the first-named guides.

10. A miter box having two sets of saw guides, one set having the guides disposed on opposite sides of the box with those guides on one side in fixed relation to the guides on the other side to provide for different angles of cut and the opposite angles thereto, and the other set of guides having the guides disposed on opposite sides of the 110 box with the guides on one side fixed thereto and greater in number than the guides on the opposite side, and the last-named guides being movable toward and from each other lengthwise of the box to provide in conjunction with the fixed guides of the same set for various angles of cut and the opposite angles and for angles of cut not provided for by the first-named set of guides.

11. A miter box having a set of saw guides 120 on one side of the work space, and having a longitudinal slot on the other side of the work space, and another slot extending transversely of the work space, other saw guides mounted on the box on the slotted 125 side of the work space, in coactive relation with the first-named slot, and connections between the second-named saw guides for causing their simultaneous movement in opposite directions, said connections being pro- 130

vided with guiding connections to the second-named slot.

12. A miter box having coacting saw guides on opposite sides of the work space, 5 with the saw guides on one side of the work space movable toward and from each other, and connected links in turn connected to the last-named saw guides, the miter box being provided with both longitudinally and lat- 10 erally extended guides for the links, and

saw guides to cause like extents of movement of the saw guides controlled by the links simultaneously in opposite directions.

In testimony, that I claim the foregoing as my own, I have hereto affixed my signa- 15 ture in the presence of two witnesses.

HENRY SIMON.
